ELEVATOR SHOE

Herbert C. Gaither, Detroit, Mich.

Application July 22, 1946, Serial No. 685,402

5 Claims. (Cl. 308—3)

2

The present invention pertains to a novel elevator shoe.

The conventional elevator shoe consists of a substantially unyielding material, and consequently noises are created between the shoe and the guide rail. The principal object of the present invention is to eliminate these noises.

Such noises occur when the shoe passes irregularities in the rail. The irregularities are caused by misalignment of rail sections, imperfect joints and anchors, and expansion and contraction of the rail sections, all of which impart jolts or shocks that are heard in the elevator cab.

Considerable effort has been expended with a view to reducing the noise produced between the guide shoes and the rails. In one such instance, for example, a shock absorbing connection is provided between the unyielding shoe and the cab. The present invention, on the other hand, provides a means for eliminating the source of the noises rather than absorbing or reducing the noises after they have been produced.

A further difficulty that accompanies the production of noise in the manner described is the wearing of the shoe by constant impact with the irregularities in the rail. The useful life of the shoe is correspondingly reduced.

The stated object of the invention is accomplished by the provision of a shoe made of a material that yields noiselessly on impact with the irregularities in the rail. The selected material, moreover, is of such character that it does not chip or become abraded on impact. Further, it is resistant to the lubricant and absorbs particles of dirt, grit, cement, metal and the like that find their way between the shoe and the rail. These particles eventually roll or work their way out of the shoe without removing any of the shoe material so that the shoe, being yielding and resilient, returns to its original shape.

It is evident that these properties do not occur in all forms of rubber. The selected material is in the nature of a synthetic rubber or elastomer known commercially as neoprene or Buna N having a durometer hardness of 40 to 60.

The high rate of wear of conventional shoes introduces a clearance between the rail and the sides of the shoe which must be regarded as normal. The clearance between the rail and the safety jaws must obviously be still greater or on the order of .010 inch. Since the shoes of this invention do not wear as much and so rapidly, the normal tolerance between the rail and the sides of the shoe is less than previously allowed. As a result, the clearance between the rail and the safety jaws is less than usual or on the order of .003 inch. When the elevator cable breaks, the more closely spaced emergency safety jaws permitted by this invention grip the rail in less time than is required with more widely spaced jaws.

with less accelerated falling of the cab, less discomfort to the passengers and considerably less damage to the equipment. Another object of the invention, therefore, is to provide a guide shoe that makes possible the advantages of more closely spaced safety jaws.

The invention is fully disclosed by way of example in the following description and in the accompanying drawings in which:

Figure 1 is a side elevation of a shoe assembly;

Figure 2 is a section on the line 2—2 of Figure 1;

Figure 3 is a section on the line 3—3 of Figure 1;

Figure 4 is a perspective view of the shoe;

Figure 5 is an elevation at the open side of the shoe, and

Figure 6 is an elevation on the line 6—6 of Figure 5.

Reference to these views will now be made by use of like characters which are employed to designate corresponding parts throughout.

In Figure 1 is shown a conventional rail of the

usual T-shape comprising a base 1 suitably fastened to the supporting structure and a rib or

flange 2 engaged by the shoe. The shoe is a U-shaped member 3 and fits slidably on the rib 2.

Successive rail sections are fitted together at mortise-and-tenon joints 4 and are fastened together by suitable means such as fish plates that are well known in the art and therefore not illustrated here.

As already indicated, the shoe is composed of a selected material that is yielding, non-abrading,

oil-resistant and self-restoring to shape. Such

a material is neoprene or Buna N of 40 to 60 durometer hardness, preferably nearer the higher limit. Neoprene is a synthetic elastomer which

is essentially a polymer of 2-chloro-1,3-butadiene or a copolymer of 2-chloro-1,3-butadiene and an

other polymerizable substance. Buna N is a synthetic elastomer which is essentially a copolymer

of butadiene and acrylonitrile.

The shoe is mounted on the elevator cab 5 by means of a bracket 6 which carries a shoe holder

7 in the usual manner. The free corners of the

sides of the shoe are notched at 8 to receive keepers 9 mounted on the upper and lower ends of the

holder. In this manner the shoe is retained in the keeper. Although illustrated and described

in connection with a cab, the shoe may also be provided on the counterweights within the scope

of the invention.

The ends of the shoe are preferably bevelled at

10 for admission of lubricant supplied from the box oiler at the upper end of the rail in the usual manner.

The joints 4 as a rule are not perfectly fitted and not perfectly tight, whereby the rail ends are permitted to shift laterally. As the shoe passes

over these imperfect joints, the familiar click is

heard in the cab equipped with conventional shoes. Moreover, the impact causes wear and abrading of the shoe, and the useful life of the shoe is thereby reduced.

The resilient shoe herein described absorbs the impact instantaneously, so that no noise is heard. Having a durometer hardness of 40 to 60 and being extremely tough as well as resilient, the material does not chip on impact with sharp corners and does not wear off against irregular surfaces. On the contrary, the material merely yields and returns to its original shape.

Particles of dust, metal, cement from the building, materials carried as the load on a freight elevator, and the like, find their way between the rail and the shoe. These are forced into the rubbing surface of the shoe to a position where they do not scratch the rail. In time they roll or otherwise work their way out of the shoe and leave no impression in the latter.

In order to facilitate the release of particles and to improve the lubrication in a manner to be set forth, the inner surfaces of the sides of the shoe are formed with a suitable number of angular grooves 11 shown in the preferred V-shape. In a shoe of conventional size these grooves are approximately $\frac{3}{4}$ inch wide at the top and about $\frac{1}{8}$ inch deep. Pockets 12 may be formed in the base of the channel to trap a quantity of lubricant which eventually flows to the grooves 11.

Embedded particles working their way out of the material are caused to travel only a relatively short distance to reach an edge of the shoe or the edge of one of the grooves 11. The sides of the grooves, being at an oblique angle to the direction of travel of the shoe, aid in expelling the particles.

Lubricant is expelled from the grooves in a similar manner accompanied by a squeegee action of the edges of the grooves against the sides of the rail. Inasmuch as the lubricant is supplied from the oiler at the upper end of the rail at a given rate, it should be taken off the rail at substantially the same rate to avoid accumulation of contaminated lubricant. The rate of supply and removal of lubricant should, ideally, be approximately the rate of contamination. The rate of supply at the oiler is easily controlled by well known means. The rate of removal at the grooves 11 is regulated by the number of grooves in the shoe and the angularity of their sides.

The high resistance of the shoe material to wear and to deterioration by lubricant leads to another important advantage in the operation of the elevator. The wear of a conventional hard shoe requires a given tolerance between the rail and the sides of the shoe. The spacing of the emergency safety jaws from the rail must obviously be still greater. Inasmuch as the safety jaws and the mechanism for operating them are well known in the art, they are not illustrated in the present instance. This spacing is approximately .010 inch at each side of the rail.

The wear-resistant rail herein disclosed requires less tolerance at the sides of the rail, and consequently the safety jaws may be spaced from the rail less than the usual .010 inch, or about .003 inch. When the jaws are operated on the breaking of the elevator cable, they have a shorter distance to travel in coming into contact with the rail. Consequently the gravity accelerated drop before braking and gripping by the jaws is considerably reduced, with proportionally less fright

and injury to the passengers and less damage to the installation.

Although a specific embodiment of the invention has been illustrated and described, it will be understood that various alterations in the details of construction may be made without departing from the scope of the invention as indicated by the appended claims.

What I claim is:

10. An elevator shoe comprising a member of yielding rubbery material and of U-shape in transverse section, the internal plane surfaces of the side walls of the member each having a plurality of independent transverse grooves spaced longitudinally of the member, each of said grooves extending from the edge of a wall inwardly toward the wall of said member connecting said side walls.
20. An elevator shoe comprising a member of yielding rubbery material and of U-shape in transverse section, the internal plane surfaces of the side walls of the member each having a plurality of independent transverse grooves spaced longitudinally of the member, each of said grooves extending from the edge of a wall inwardly toward the wall of said member connecting said side walls, each of said grooves having side walls converging toward said connecting wall of the member.
30. An elevator shoe comprising a member of yielding rubbery material and of U-shape in transverse section, said material having a durometer hardness of 40 to 60, the internal plane surfaces of the side walls of the member each having a plurality of independent transverse grooves spaced longitudinally of the member, each of said grooves extending from the edge of a wall inwardly toward the wall of said member connecting said side walls.
40. An elevator shoe comprising a member of yielding rubbery material and of U-shape in transverse section, the internal plane surfaces of the side walls of the member each having a plurality of independent transverse grooves spaced longitudinally of the member, each of said grooves extending from the edge of a wall inwardly toward the wall of said member connecting said side walls, the inner surface of said connecting wall having a recessed formation therein adapted to collect lubricant.
50. An elevator shoe comprising a member of yielding rubbery material and of U-shape in transverse section, said material having a durometer hardness of 40 to 60, the internal plane surfaces of the side walls of the member each having a plurality of independent transverse grooves spaced longitudinally of the member, each of said grooves extending from the edge of a wall inwardly toward the wall of said member connecting said side walls, the inner surface of said connecting wall having a recessed formation therein adapted to collect lubricant.
60. An elevator shoe comprising a member of yielding rubbery material and of U-shape in transverse section, said material having a durometer hardness of 40 to 60, the internal plane surfaces of the side walls of the member each having a plurality of independent transverse grooves spaced longitudinally of the member, each of said grooves extending from the edge of a wall inwardly toward the wall of said member connecting said side walls, the inner surface of said connecting wall having a recessed formation therein adapted to collect lubricant.
